AUTOMATIC GAIN CONTROL

William S. Barden, Stapleton, Staten Island,
N. Y., assignor to Radio Corporation of Amer-
ica, a corporation of Delaware

Application April 15, 1931, Serial No. 530,267

8 Claims. (Cl. 250—20)

My present invention relates to amplifiers, and more particularly to an automatic gain control arrangement for use in connection with a radio frequency amplifier circuit.

It is well known in the prior art to employ an accumulator device in the grid circuit of a detector tube to secure automatic volume control of a radio receiver. Generally, such an arrangement comprises a capacity in series between the cathode and grid of the detector tube, and a resistor connected in shunt with the capacity. The operation of such a gain control arrangement may be explained by pointing out that signal energy, applied to the input circuit of the detector tube, whose peak voltage magnitude exceeds the detector grid bias value results in the charging of the aforementioned series capacity due to grid current. The effective detector grid bias is, then, the sum of the fixed and accumulated biases.

It is, of course, obvious that the accumulated bias, in such a case, is variable with signal field strength, and, also, with percentage modulation. The consequent changes in bias result in surges in the audio frequency system, with the result that there simultaneously occurs surging of the reproducer diaphragm. Other forms of distortion and undesired effects may, also, result. For example, the variation of detector grid bias comprises an obstacle to the desired automatic volume control operation.

Now, I have discovered a method of, and devised novel means for, eliminating the aforementioned difficulties in an automatic gain control arrangement of the type described, the method consisting in associating a two electrode space discharge system with the control electrode and cathode of the detector tube, and disposing the accumulator control circuit in the said two electrode system, with the result that the accumulator control circuit is operated by the two electrode system; and the detector tube has a fixed bias applied at all times to its control electrode, as is desired for optimum reception and reproduction of signal energy.

Accordingly, it is one of the main objects of my present invention to provide an automatic gain control arrangement for a radio receiver, the arrangement comprising a two electrode space discharge tube disposed in the input circuit of the receiver detector tube, and an accumulator circuit connected between the two electrodes of said space discharge tube whereby the detector stage of a radio receiver may be employed for signal translation as well as automatic gain con-

trol of the radio frequency amplifier, and yet the two functions of gain control and translation be independent of each other.

Another important object of the present invention is to provide in a radio receiver including a radio frequency amplifier and a detector tube, a diode connected in shunt with the control electrode and cathode of the detector tube, and an accumulator circuit including a capacity connected in series between the electrodes of the diode, a resistor in shunt with said capacity, and additional means for connecting a point on the input of the diode, to one, or more, points in the grid circuits of the radio frequency amplifier.

Other objects of the invention are to improve generally the efficiency of automatic gain control arrangements of the present type, and to particularly provide a gain control receiver which is not only reliable in operation, but economically manufactured and assembled.

The novel features which I believe to be characteristic of my invention are set forth in particularity in the appended claims, the invention itself, however, as to both its organization and method of operation will best be understood by reference to the following description taken in connection with the drawing in which I have indicated diagrammatically one circuit organization whereby my invention may be carried into effect.

Referring to the accompanying drawing, there is shown, merely by way of illustration, a radio receiver of the so-called tuned radio frequency amplifier type. The receiver in its usual form includes a grounded antenna system 1, which is coupled, as at M₁, to the input circuit of the first radio frequency amplifier tube 2, the said input circuit being tuned by a variable condenser 3. The output of the tube 2 is coupled, as at M₂, to the input circuit of a second radio frequency amplifier tube 4, the input circuit of this tube being tuned by a variable condenser 5. While two stages of radio frequency amplification have only been shown, it is to be clearly understood that as many tuned stages as is desired may be employed.

The amplified output of the last amplifier tube is impressed, through a coupling M₂, upon the input circuit of a detector tube 6, the latter including the usual series capacity 7 in the grid circuit thereof, and a grid leak 8 for detection purposes. The detected output is impressed, through an audio frequency transformer coupling M₃, upon any well known type of utilization means. The latter may be one, or more, stages

of audio frequency amplification followed by any type of reproducer well known to those skilled in the art, as, for example, a loud speaker of the electromagnetic, or electrodynamic type, or any other type of reproducer of audio frequency impulses.

The anode circuit of each of the tubes 2, 4 and 6 includes a source of anode potential B, these sources being shown independent for the sake of simplicity of description only, it being clearly understood that other types of potential sources may be readily applied to the present invention, such sources being numerous and well known in present power supply practice. Furthermore, the control electrodes of each of the tubes 2, 4 and 6 are shown biased by means of resistors R disposed in the low potential, or ground, sides of the cathodes of these tubes.

In order to maintain the amplification of the amplifier stages, including the tubes 2 and 4, at a predetermined level, there is provided an automatic gain control arrangement. The latter comprises a diode 9 having its anode connected to the grid circuit of the detector tube 6, and its cathode to the ground side of the cathode of the detector tube. In other words, an auxiliary space discharge system including an anode and cathode is disposed in shunt to the control electrode and cathode of the usual detector tube. An accumulator circuit comprising a fixed capacity 10 and a resistor 11, the latter being in shunt with the capacity 10, is connected in series with the grounded leg of the diode cathode.

23 A conductor 12 is connected between the high potential side of the accumulator circuit and the grid circuits of the amplifier tubes 2 and 4, the conductor being connected to the low potential sides of the aforementioned grid circuits in a manner well known to those skilled in the art.

40 A blocking capacity 13 is disposed between the anode potential source B and the gain control connection to each grid circuit in each of the amplifier stages.

45 The operation of the automatic gain control mechanism is believed to be clear from the above description. It is pointed out, in review, that the accumulator circuit 10, 11 is operated by the diode 9, and the detector tube 6, by virtue of the present arrangement, has a fixed bias applied to its control electrode, as is desired in an arrangement of this type. When signal energy above a predetermined value is applied to the input circuit of the detector stage, the internal impedance of the diode 9 will be of such a magnitude that it will 50 become conductive, or in other words break down and permit the flow of current therethrough, with the result that the capacity 10 becomes charged.

55

62 The direct current potential accumulated across the circuit 10, 11 is, then, utilized to control the grid bias of the amplifier tubes 2 and 4. Obviously, when the signal energy applied to the input of the detector tube 6 exceeds the desired predetermined value, the direct current potential developed across the accumulator circuit will 63 serve to increase the bias on the grids of the amplifier tubes. The amplification will, then, be decreased sufficiently to restore the magnitude of the energy applied to the detector input to the desired level. The reverse action, of course, takes 70 place whenever the signal energy applied to the input circuit of the detector tube falls below the desired level. In this way, the gain of the radio frequency amplifier stages is maintained uniform.

75 It will now be appreciated that there has been

provided by means of the present invention a simple arrangement, employing an accumulator circuit in the detector input, for controlling the gain of a radio frequency amplifier, the particular feature of the present arrangement residing in the fact that the gain control arrangement does not interfere with the detector action of the detector stage due to the use of an auxiliary diode in the input circuit of the detector tube.

While the present receiver has been shown to be of the tuned radio frequency type, it is to be understood that the invention is not limited to such a receiver. However, for simplicity of description, the input circuits of the tubes 2, 4, and 6 are shown as having their tuning condensers arranged for mechanical uni-control, as denoted by the dotted line 20, it being pointed out that the variable condenser 21 is employed for tuning the input circuit of the detector stage.

While I have indicated and described one arrangement for carrying my invention into effect, it will be apparent to one skilled in the art that my invention is by no means limited to the particular organization shown and described, but that many modifications may be made without departing from the scope of my invention as set forth in the appended claims.

What I claim is:

1. In combination, in a gain control system for
a radio receiver, a multi-tube radio frequency am-
plifier, a detector tube having an input circuit,
a diode disposed between the input electrodes of
the detector tube, a condensive accumulator cir-
cuit connected in series between the diode elec-
trodes and between the detector input electrodes,
and a conductive connection between the accumu-
lator circuit and the grid circuit of at least one
tube in the radio frequency amplifier, said con-
ductive circuit being connected in series with the
detector input circuit. 105
110
115

2. A radio receiver comprising at least one stage of radio frequency amplification including an electron discharge tube, a detector tube coupled to the output circuit of the amplifier tube, a space discharge device including at least two electrodes connected in the input circuit of the detector tube, a capacity between the electrodes of the space discharge device, a resistor in shunt with said capacity and in series with the detector input circuit, means independent of said device for keeping the detector grid fixedly biased at all times, and a connection between one side of said capacity and the grid circuit of said amplifier tube. 120 125

3. A radio receiver comprising at least one stage of radio frequency amplification including an electron discharge tube, a detector tube coupled to the output circuit of the amplifier tube, a diode connected in the input circuit of the detector tube and having its anode connected to the detector grid and its cathode connected to the detector cathode, a capacity connected in series between the electrodes of the diode, means for biasing said detector grid, a resistor in shunt with said capacity and in series with the detector input circuit, a connection between one side of said capacity and the grid circuit of said amplifier tube, and said diode preventing potential variations across said resistor from affecting said detector grid 145 bias. 130 135 140 145

4. A radio receiver comprising at least one stage of radio frequency amplification including an electron discharge tube, a detector tube coupled to the output circuit of the amplifier tube, 150

- a diode connected in shunt with the input electrodes of the detector tube, a capacity in series between the electrodes of the diode, a resistor in shunt with said capacity and in series with 5 the detector input circuit, a detector grid bias means in the detector cathode circuit, a connection between one side of said capacity and the grid circuit of said amplifier tube, said diode maintaining the detector grid bias free from variation by potential changes across said resistor. 10 5. In a high frequency receiving circuit, an amplifier, means connected with an electrode of the amplifier for controlling the transmission efficiency of the amplifier, a detector having an input circuit, said means including a condensive network connected between the input electrodes of the detector and in series with the detector input circuit, and a space discharge path connected in shunt with said network for developing 15 a potential across said network when signals applied to the amplifier input exceed a predetermined intensity, and means independent of said path and network for maintaining a fixed bias on the detector grid throughout development of said 20 potential. 25 6. In a high frequency receiving circuit, an amplifier, means connected with the input electrode of the amplifier for controlling the transmission efficiency of the amplifier, a detector having an input circuit, said means including a condenser-resistance network connected between the input electrodes of the detector and in series with the detector input circuit, and a space discharge path connected in shunt with said network for developing 30 a potential across said network when signals applied to the amplifier input exceed a predetermined intensity, and means connected between the detector grid and cathode, and independent of said path, for maintaining a substantially fixed bias on the detector grid at all times. 35 7. An automatic gain control system for a radio frequency amplifier comprising a rectifier circuit including an electron discharge tube, a control network in series between the input electrodes of the tube, the latter electrodes being coupled to the amplifier output, a diode in shunt with the network and connected between said input electrodes, and a conductive connection between one side of the network and an amplifier input electrode. 80 8. An improvement in an automatic volume control arrangement for high frequency amplifiers of the type comprising a detector having its input circuit coupled to said amplifier, means for biasing the detector grid being disposed between the grid and cathode of the detector, a condenser-resistor accumulator network being connected between the detector input electrodes in series with said detector input circuit, and a gain control electrode of said amplifier being conductively connected to one side of said network, said improvement including a space discharge device connected across the said input electrodes, one electrode of said device being connected to the other side of said network, and a capacity disposed between the device and the grid of said detector, said device and capacity preventing potential changes across said network from affecting the detector grid bias. 85 90 95 100 105 110 115 120 125 130 135 140 145 150
